(57) **CLAIM**

The ornamental design for an electronic vaporizer, as shown and described.

DESCRIPTION

FIG. 1 is a perspective front view of an electronic vaporizer.

FIG. 2 is a front view of the electronic vaporizer of FIG. 1.

FIG. 3 is a rear view of the electronic vaporizer of FIG. 1.

FIG. 4 is a right side view of the electronic vaporizer of FIG. 1.

FIG. 5 is a left side view of the electronic vaporizer of FIG. 1.

FIG. 6 is a top view of the electronic vaporizer of FIG. 1.

FIG. 7 is a bottom view of the electronic vaporizer of FIG. 1.

FIG. 8 is a front perspective view of the electronic vaporizer of FIG. 1, shown assembled with a pod.

FIG. 9 is a front exploded view of the electronic vaporizer and pod assembly of FIG. 8.

FIG. 10 is a rear perspective view of the electronic vaporizer and pod assembly of FIG. 8; and,

FIG. 11 is a rear exploded view of the electronic vaporizer and pod assembly of FIG. 8.

In the drawings, the evenly-spaced broken lines show portions of the electronic vaporizer that form no part of the claimed design; the dash-dot-dash lines represent boundaries of the claims design and form no part thereof.
